UNITED STATES PATENT OFFICE.

LANGFORD J. BOWNE, OF HOWARD BEACH, NEW YORK, AND HORACE W. ULRICH, OF EAST ORANGE, NEW JERSEY, ASSIGNEES TO WESTERN ELECTRIC COMPANY, INCORPORATED, OF NEW YORK, N. Y., A CORPORATION OF NEW YORK.

TELEPHONE SYSTEM.

Application filed December 31, 1924. Serial No. 759,195.

To all whom it may concern:

Be it known that we, LANGFORD J. BOWNE and HORACE W. ULRICH, citizens of the United States of America, residing at Howard Beach, Queens County, New York, and East Orange, Essex County, New Jersey, respectively, have invented certain new and useful Improvements in Telephone Systems, of which the following is a full, clear, concise, and exact description.

This invention relates to telephone systems and more particularly to two-way inter-exchange trunk lines and connecting cord circuits therefor adapted to be used in a multi-exchange system.

The object of the invention is to provide improved means for increasing the operating efficiency, and effecting installation economies in systems of this character.

The invention hereinafter described is particularly applicable to a system comprising a plurality of private branch exchanges. In such systems it is desirable to be able to interconnect any one subscriber's line with any other subscriber's or central office line, terminating either at the same or at different switchboards of the system. For the purpose of describing this invention, the circuit arrangement hereinafter described for interconnecting any two of such private branch exchange switchboards will be called a "through and terminating tie line" and a connection of two such tie lines at any private branch exchange will be referred to as a "through tie line connection."

A feature of the invention resides in a circuit arrangement for tie lines of the character described which automatically discriminates between tie line to station, tie line to central office and through tie line (tie line to tie line) connections whereby a repeating coil is included in the tie line to station and in the tie line to central office connections and a direct talking path, from which the repeating coils and associated equipment are absent, is provided for through tie line connections.

The tie line of the present invention is adapted to function under all conditions with standard private branch exchange cord circuits similar to the one disclosed in Patent No. 1,559,297, granted October 27, 1925, to Walter P. Albert, thereby making it unnecessary to provide at each switchboard so-

called universal cord circuits or other special equipment heretofore employed for making through connections from one tie line to another.

More specifically, when the back plug of a standard P. B. X. cord, similar to the cord circuit described in the aforementioned co-pending application, is inserted in a jack associated with a tie line according to this invention the tie line discriminates between battery normally supplied by the cord for station connections and the battery supplied by a line to which the front cord may be connected, that is, a central office trunk line or another "through and terminating tie line", and it further discriminates between the battery current supplied by these two latter types of lines. In case a cord circuit is connecting two "through and terminating tie lines" battery current from the tie line to which the front cord is connected causes apparatus associated with both tie lines to function to remove the normally connected repeating coils and associated equipment from both tie lines and to connect the tie lines through as hereinbefore mentioned.

Another feature of the invention resides in the provision of means, associated with a standard P. B. X. cord circuit, responsive to the operation of a monitoring key associated with said cord circuit, to disconnect the low impedance talking circuit of the operator's telephone set from the cord in case any talking key at the position is operated; to connect the operator's receiver to the cord through a high impedance transformer for the purpose of minimizing transmission losses during monitoring and to prevent the connection of a second cord circuit with said first cord circuit in case the talking key of the second cord circuit is operated during the period the monitoring key of the first cord circuit is operated.

Still another feature resides in the provision of means comprising a selector and a relay associated with the incoming end of a railway message telephone line which terminates at a P. B. X. in a tie line circuit in accordance with this invention whereby selective impulses transmitted over the message line from an outlying station cause said selector to function to cause said relay to initiate a call over the tie line equipment in the usual manner herein described.

Other features, not specifically mentioned, including further discrimination means and provision for supervision under all conditions of the line, will more readily appear from the following description of the invention in conjunction with the accompanying drawings in which a tie line embodying the invention is shown together with sufficient connecting apparatus to properly illustrate the invention.

Referring to the drawings:

Fig. 1 shows one end of a tie-line according to the present invention terminating in a private branch exchange switchboard with which may be connected a cord circuit shown in Fig. 2.

Fig. 1^a represents a trunk to a central office, terminating at the same private branch exchange as the tie-line herein described, with which connections may be made as hereinbefore mentioned.

Fig. 1^b represents the circuit arrangements for the extension of the tie-line of Fig. 1 to another private branch exchange where it terminates in a similar circuit arrangement; and Fig. 1^c represents an arrangement for connecting the tie-line circuit of Fig. 1 to a railway message telephone line equipped with selector equipment.

Figs. 3, 3^b and 3^c are duplicates of Figs. 1, 1^b and 1^c, except that the circuit arrangement is shown in reverse order. The cord circuit in Fig. 2 is designed to interconnect the tie-lines illustrated in Figs. 1 and 3.

Fig. 3^a represents a subscriber's line served by the private branch exchange.

It should be understood that the system is readily adaptable for extending dial station lines terminating in automatic switches, not shown, which switches have access to the P. B. X. attendant. Also, central offices associated with the private branch exchange, as for example in Fig. 1^a, may either be semi-automatic or automatic, as well as manual. For purposes of this description, the drawings have included only that necessary to an understanding of the invention.

Fig. 2^a is a schematic of an intercommunicating multi-exchange telephone system to which the invention is particularly applicable. Private branch exchanges at five cities, Boston, New Haven, New York, Philadelphia, and Washington, are shown linked together by tie lines. The rectangular boxes on either side of the circles representing the respective P. B. X.'s at each city indicate an end of a tie-line capable of forwarding or terminating a connection from another private branch exchange. The small circles designated V, W, X, Y and Z represents central offices, the smaller circles a, b, c, etc. to g represent subscribers of a central office or stations of a private branch exchange and the small square h a railway train dispatcher's station on a railway mes-

sage telephone line terminating in tie line equipment at the Washington P. B. X.

A detailed description of the operation of the system will now be given.

Considering Fig. 3, on incoming calls from a distant private branch exchange, relay 10 operates in a circuit from the distant loop, tip of the line, contact 15 of relay 11, upper contact of relay 12, upper right-hand winding of repeating coil 13, condenser 14, winding of relay 10, lower right hand winding of repeating coil 13, lower normal contact of relay 12, contact 16 of relay 11, ring of line, to distant P. B. X. Relay 10 causes relay 17 to operate in a circuit comprising ground 18 of lead B of Figure 3^b which is the normal arrangement, contact 19 of relay 10, contact 21 of relay 20, winding of relay 17, normal contact 22 of relay 23 and battery 24. Relay 17, upon its energization locks up to ground 25 at its alternate contact 26, and lights line lamp 27 in an obvious circuit including battery 28, and contact 29 of relay 17, to ground 31 at the lamp. Busy signal 32 will also be set in a circuit from battery 28, contact 30, to ground at the signal.

If the call, on the other hand, be considered incoming to the end of the tie-line shown in Fig. 1, a similar operation would take place, relays 210 and 217 operate, lamp 227 lights, and make busy signal 232 is set.

For simplicity, however, the operation in the answering of an incoming call will be described only in conjunction with Fig. 3. As the tie-line is handled on a station basis, it is answered with the rear cord of the cord circuit (shown in Fig. 2). The attendant upon noting the illumination of lamp 27 will insert the rear plug of the cord into jack 33 of the tie-line. The tip spring of the jack will, therefore, serve to close the local contact to ground 34. Thereupon relay 35 will operate in a circuit as follows: battery at relay 35, winding of relay 35, resistance 36, armature and contacts 59 of relay 28, contacts 37 and armature of relay 38 to ground 34. Relay 35 by closing its contacts 40 thereupon causes relay 39 to operate in a circuit from battery of relay 39, outer normal contacts of relay 41, normal back contact of relay 42, contacts 43 of relay 39, contacts 40 of relay 35 to ground 34. Relay 39 locks up to ground 34 through its contact 44, in a circuit including outer normal contacts of relay 41, outer normal contacts of relay 42, contacts 44 of relay 39 and contacts 37 of relay 38. Relay 39 also closes the circuit to relay 45 at its contacts 46 which may be traced from battery of relay 45, outer right-hand normal contact of relay 23, contacts 46 of relay 39, 37 of relay 38 to ground 34 at the jack. Relay 45 will then lock up in a circuit in-

cluding its contact 47, contacts 40 of relay 35 to ground 34. Relay 39, in pulling over its outer left-hand armature closes a circuit to cause the operation of relay 48 through inner left-hand contacts of relay 49 to ground 34 at the jack, but this relay performs no useful functions at this time.

The operation of relay 45, will cause relay 23 to operate: battery 24, winding of relay 23, contacts 50 of relay 45 to ground 34; and lock up to ground 34 through its alternate outer left-hand contacts and contacts 37 of relay 38. Relay 23 will then cause relay 17 to deenergize by pulling over its inner right-hand armature and opening contacts 22 to disconnect battery 24 therefrom. The pulling over of this armature will connect battery 24 to hold busy signal 32 operated after relay 17 releases. Relay 17, in releasing extinguishes the line lamp 27 to note the answering of the call. Cut off relay 23 in pulling over its outer right-hand armature opens the path from the make contact 46 of relay 39 to the winding of relay 45 to prevent future false operation of relay 45. Relay 45, however, will not release at this time, being locked up at ground 34 through its contacts 47 and contacts 40 of relay 35. Relay 23, in operating, also opens the operating path to the winding of relay 35 through resistance 36 at contacts 59. Relay 35 will, therefore, be cut off from ground 34 and failing to find a holding ground, releases. It should be noted that with the rear cord in the jack there is no ground on the sleeve of the cord. Relay 35 in releasing, opens contacts 40, in turn releasing relay 45. Relay 23 also closes the circuit through winding of relay 20 at its contacts 52 from battery 51. The circuit finds a holding ground at 34 through contacts 37 of relay 38. Relay 20 operates slowly. Finally, relay 23 by closing its inner left hand armature contacts connects ground 34 through the normal contact of relay 35, when it releases, to the sleeve of the jack through contacts 37 of relay 38. This ground on the sleeve of the jack provides a ground for supervisory lamps 101 and 102 in the cord circuit, and serves for an audible busy signal when a busy test is made on the sleeve of a multiple jack.

Relay 20 in operating opens at its contacts 21 the path from the front contact 19 of ringing relay 10 to the winding of relay 17, to prevent the possible operation of this relay on a re-ring. It also opens the short circuit of the winding of relay 53 by pulling over its left-hand armature. Primarily, relay 20 connects the ring side of the jack through the lower left-hand winding of repeating coil 13, left-hand make contacts of relay 20, normal left-hand contacts of relay 45 to winding of relay 54, winding of relay 55, then back through the

right-hand normal contact of relay 45 to the tip of the line through upper left-hand winding of repeating coil 13. The result of connecting relays 54 and 55 across the rear cord is to cause the operation of the rear supervisory relay 103 and the extinguishment of rear lamp 101, in a circuit as follows:—grounded battery 104, inner left-hand normally closed contacts of relay 105, winding 106 of retardation coil 107, contacts 108 of through dial and night key 109, winding of relay 103, to ring of the plug and jack, through the loop including relays 54 and 55, as hereinabove described, back through the tip of the jack, tip of plug, contacts 110 of key 109, winding 111 of coil 107, right-hand normal contacts of relay 105, to ground.

Front lamp 102 remains lighted inasmuch as front supervisory relay 112 remains normal, the circuit path running from grounded battery 113, through the lamp, outer left-hand contacts of relay 105, normal contacts of relay 112 to ground on sleeve of jack.

It may now be noted that on calls to stations, the station receives a greater amount of transmitter battery than on average station to station calls, due to the comparative high resistance of relays 54 and 55 in the loop.

Polarized relay 54, in operating on the cord battery 104, closes the circuit to the windings of the relays 41 and 56 in a path as follows:—battery and windings of relays 41 and 56, make contact of relay 54, normal armature contact of polarized relay 55, which is not operated on the cord battery, to ground 34. Relay 41, thereupon opens the circuit to the winding of relay 39 which releases. No further operation of the circuit takes place on calls to stations or calls to central office trunks on which the battery is poled the same as the cord circuit battery. On calls to other through and terminating tie-lines or to central office trunks which supply reverse battery before or after the called party answers; and hence variously and differently affect polarized relays 54 and 55, there is further functioning of this circuit, as will hereinafter be explained.

Considering now the operation of the circuit on outgoing calls from stations or other types of tie-lines; such stations as for example *e* or *f* as illustrated in Fig. 2^a are answered with the rear plug of the cord and their extension is affected by the insertion of the front plug in the forwarding tie-line (as 302 or 303 depending on the extension desired):—When the front plug of the cord is inserted in the tie-line jack of Fig. 1 (the same operation taking place if the circuit arrangement per se in Fig. 3 were considered) the auxiliary contact on the jack closes the circuit from ground 234

to the winding of relay 235 through resistance 236. The circuit extends from battery, winding of relay 235, resistance 236, contacts 259 of relay 223, contacts 237 of relay 238 to ground 234. Relay 235 operates and connects the sleeve of the jack to a point 297 between the winding of relay 235 and resistance 236, through its alternate left-hand contacts. It should now be observed that relay 105 of the cord circuit is connected from ground to the sleeve of the front cord, and therethrough to battery of the relay 235. As a result of the difference of potential between the sleeve of the front cord and the point 297 between relay 235 and resistance 236, relay 105 of the cord will operate; the winding of relay 235 is shunted by resistance 270 to provide sufficient current from battery of relay 235 through relay 105 to cause said relay to operate. Relay 105, in operating removes the battery on the ring and ground on the tip of the line; and bridges winding 111 of retardation coil 107 across the cord circuit in a path from tip of the cord, upper normal contacts of relay 114, contacts 110 of key 109, winding 111 of coil 107, make right-hand contact of relay 105, normal contacts of relay 115, contacts 116 of key 109, normal back contacts of relay 114 to ring of the cord. When relay 235 operated, it closed the circuit at its outer right-hand contacts to relay 239, through contacts of relays 241, 242 and 239. Relay 239 thereupon operates, locks up to ground 234 through its alternate left-hand contacts, and in turn closes the circuit to the winding of relay 245:—from battery, winding of relay 245, outer normal left-hand contacts of relay 223, inner left-hand alternate contacts of relay 239 to ground 234 as hereinbefore described. Relay 239 also closes the circuit at its outer right-hand alternate contacts to relay 248 which operates, but performs no useful function at this time. Relay 245 locks up to ground 234 through its inner left-hand contacts and outer right-hand contacts of relay 235. Relay 245 in pulling up its outer contacts on either side, now disconnects relays 254 and 255 from windings of the repeating coil 213 and instead transfers the tip and ring of the line through the windings of the repeating coil to the windings of retardation coil 257 and the winding of relay 258. The detailed circuit changes will be later described. It should be observed, however, that the circuit path from the upper right-hand winding of repeating coil 213 proceeds from battery of retardation coil 257, and that the lead from lower right-hand winding of repeating coil 213, is opened at the contacts of relay 220. It is due to this break in the circuit that the loop from the dry bridge including winding 111 of the retardation coil in the cord circuit, and including relay

258, is not completed at this time. It may also be noted that relay 242 is short circuited by the armature normal contacts of relay 258 in an obvious circuit. Relay 245 upon energizing closes the circuit at its inner right-hand contacts from ground 234 to the winding of relay 223 which operates, and locks up to ground 234 through its inner operated contacts 259 and contacts 237 of relay 238.

Relay 223 in operating opens at contacts 259 the ground through resistance 236 to relay 235, which does not release at this time but now holds up in series with relay 105 in the cord circuit. Relay 223, incidentally connects battery at its left-hand alternate contacts to the winding of the busy signal to operate it. Also, in pulling over its outer left-hand armature relay 223 opens the connection between the winding of relay 245 and the inner left-hand contacts of relay 239. This is to prevent future false operation of relay 245. Its main function, however, is to close the circuit to the winding of relay 220 which opens the obvious short circuit on the winding of relay 253 and closes the loop consisting of the dry bridge of the cord and the windings of relay 258 as follows:—battery and winding of retardation coil 257, alternate left-hand contacts of relay 245, upper right-hand winding of repeating coil 213, tip of jack and plug, upper normal contacts of relay 114 in the cord, through the upper normal contacts of key 109, winding 111 of coil 107, right-hand inner alternate contacts of relay 105, through obvious contacts of key 109 and relay 114, ring of plug and jack, lower right-hand winding of repeating coil 213 alternate right-hand contacts of relay 220, outer right-hand alternate contacts of relay 245, upper winding of retardation coil 257, winding of relay 258 to ground at 234. Upon the energization of relay 258 and the attraction of its armature the obvious short circuit on relay 242 will be removed, and relay 242 will as a result operate. Relay 242, then opens the circuit at its outer contacts serving relay 239, which thereupon releases. Incidentally upon the release of relay 239 and the return of its outer right-hand armature to normal, relay 248 will release. Relay 242 also is designed to close the circuit at its inner contacts from its secondary winding and the winding of relay 211 to normal contacts of relay 258. Relay 258 however, is purposely operated at the same time, as above described, and serves to prevent relay 211 from operating and relay 242 from locking up to ground 234.

Transmitter battery for the station on the rear cord as for example that illustrated in Fig. 3^a is fed from the battery at retardation coil 257 in the loop including the windings of relays 242 and 258 which remain operated.

The part of the loop circuit in the cord may be traced as follows:—tip of front jack and cord, tip of rear cord and jack, through the station, back through rear jack and cord, 5 winding of relay 103, (which energizes and closes a circuit for relay 115 from battery 104 through inner left-hand armature of operated relay 105), contacts 108 of key 109, right contacts of relay 115 now energized 10 and closing a short circuit on the winding of relay 112, contacts 116 of key 109 back to ring of plug and jack to ground in the tie-line as hereinbefore described.

It may here be explained that on calls 15 from tie-line to station or station to tie-line as just described, the repeating coils and associated equipment i. e., the retardation coil, the relays 242 and 258, etc., are so arranged, that talking battery from current source 257 20 is supplied to the station, and for supervision in the cord circuit, while at the same time, station battery is effectively prevented from reaching the toll line and from interfering with toll line apparatus.

25 Provision is made for re-ring supervision from the tie-line when either the front or rear plug is in the jack as follows:—When the rear plug is in the jack, (using Fig. 3 for illustrative purposes), relay 35 is normal and relay 20 is operated, as hereinbefore described. On a re-ring from the tie-line by the operation of the usual ringing key, at the distant station (not shown), relay 10, 30 bridged across the line, will obviously operate, and shunt down relay 20 by closing a circuit from battery 51, through its contacts 19 to ground 18 of lead B. The shunting of relay 20, and the restoration of its left-hand armature causes the opening of the supervisory bridge on the inside of the repeating coil which as hereinbefore completely traced, 35 includes relays 54 and 55, and as a result supervisory relay 103 in the cord circuit is released. In consequence lamp 101 lights. 40 Upon the completion of the ring, relay 10 releases, whereupon relay 20 again operates, pulls over its left-hand armature to complete the loop and thus causes supervisory relay 103 to reenergize and lamp 101 to be 45 extinguished.

When the front plug is in the jack (again using Fig. 3 for illustrative purposes, although Fig. 1 might equally be used) relay 35 remains operated, as described above, and prepares an operating path through its inner left-hand closed contacts for relay 60. On the re-ring from the tie-line, relay 10 is 50 operated and relay 20 releases as hereinbefore described. Relay 60 then operates in a circuit from battery, winding of relay 60, inner left-hand contacts of relay 35, normal right-hand contacts of relay 17, restored contacts 21 of relay 20, inner contacts of operated relay 10 to ground 18 of lead B. Relay 60 in operating pulls up its armatures

and connects ringing current to the tip and ring of the line, and thus to the cord circuit to operate ringing supervisory relay 40, in an obvious circuit. Relay 159, in series with condenser 160 controls lamp 102. As long 50 as ringing current is supplied relay 60 in the tie-line, and relay 159 in the cord remain operated and hence lamp 102 will light in an obvious circuit to ground at relay 159. At the end of the ring, relays 60 and 159 will 55 release and lamp 102 go out. It may be remarked that relay 20 is made slow releasing so that it will not release in case relay 10 operates momentarily due to disturbance or on surges from the tie-line. Only the 60 application of steady ringing current will effect the operation outlined. The purpose of heavy resistance shunt 61 on the winding of relay 10 is to make relay 10 unresponsive to morse thumps which may be impressed on the line and thus on the relay, when the tie-line is composited. Resistance 61, is arranged to effectively absorb the peaks of any morse impulses, so as to prevent relay 10 65 from operating long enough to effect the restoration of slow-to-release relay 20. 70

The circuit operation, on an outgoing ring, with the front cord in the jack will now be described. (For consistency with the previous description, Fig. 1 will now be used for illustrative purposes). As shown hereinbefore, relays 235, 245, 223, 220, 242, and 258 are all operated in the tie line associated with the front cord. In order to ring over the line, the attendant will operate the usual ringing key in the cord circuit, associated with the front cord. Relays 242 and 258 will release on the opening of the cord circuit bridge by the actuation of the ringing key. Also this release takes place immediately before the ringing current is applied; i. e., immediately after the opening of the cord circuit bridge and during the infinitesimal interval before the key contacts to connect ringing current to the line. Relay 242 releases first and breaks its locking circuit when its inner armature restores, before relay 258 closes its back contacts. This is due to relay 258 being slower to release than relay 242. As a result, relay 242 is assured restoration without danger of finding a holding ground through the back contacts of relay 258. 90

When the ringing current is connected by the ringing key contacting, ringing relay 253 operates in an obvious circuit through the jack, plug, and repeating coil 213 and closes the circuit to relay 212, through the inner contacts of relay 253 and ground 95 through the jack. Relay 212, upon operating, obviously opens the line from the repeating coil and connects it to the associated ringing circuit. Ringing will thus be effected by the attendant. On the complete restoration of the ringing key in the cord, re- 100 105 110 115 120 125 130

lay 258 will again operate and will remove the obvious short circuit on relay 242, thus allowing it again to operate in series with relay 258 and the dry bridge of the cord circuit, as hereinbefore explained and described.

The circuit condition of the line termed a through tie-line connection with the rear cord in the tie-line jack, will now be considered. If a tie-line, for example, one from Philadelphia as illustrated in Fig. 2^a, which had been answered by a rear cord at tie-line 300 in New York is to be connected to another tie-line, New Haven, the connection is known as a through tie-line connection, and there is no need for battery, or ground, or for the repeating coils to be in the circuit at the New York exchange. The circuits at the New York office, are therefore, designed to recognize each other and to advance in condition to their through tie-line positions in which relays 211 or 11, respectively, in Figs. 1 and 3 are operated and effect a through, clear unimpeded line, obviating the usual transmission losses.

With the answering rear cord of the cord circuit in the tie line jack (of Fig. 3) relays 54 and 55 are bridged across the line in a circuit including battery source 104 in the cord, etc., all as hereinbefore explained in the description dealing with the answering of incoming calls with the rear cord. As described relay 54 operates on the straight cord battery, whereas relay 55 in series therewith but of opposite polarity does not operate. Upon the actuation of relay 54, relays 41 and 56 operate from the battery sources associated therewith, through the alternate contacts of relay 54 to ground 34 as hereinbefore described.

Now, when the front cord of the cord circuit is inserted in another tie line jack (as for example that of 301 at New York in order to forward the call) as represented in Fig. 1, relay 105 operates in the cord circuit, as explained in the description dealing with outgoing calls from station or other tie lines. This removes battery 104 and ground normally connected to the inner right hand armature of relay 105, from the cord circuit, and allows the relay 54 to release, which in turn releases the relay 41 (which performs no useful function at this time) by breaking the path to holding ground 34. Upon the restoration of relay 54 and the breaking of its alternate contacts, relay 56 starts to release very slowly, it being a slow release relay. Relay 54 closes its back contacts before relay 56 releases, in turn closing the circuit through the operated contact of relay 56 to the winding of relay 39 which operates and locks up in a path as follows: battery and winding of relay 39, outer normal contacts of relay 41, outer normal contacts of relay 42, contacts 43 of relay 39,

operated contacts of relay 56, normal contacts of relays 54 and 55, to ground at 34.

When relay 220 in the tie line circuit on the front cord operates, as was described, it closes ground through the windings of relay 258 and the repeating coil in that circuit to the ring side of the line and battery through a winding of the retardation coil to the tip side of the line. This battery it will be noticed is reversed to that received from the cord (i. e. the battery received from the cord circuit is connected to the ring side of the line, and ground is on the tip side). As a result polarized relay 55 in the tie line circuit on the rear cord, while unaffected heretofore, although included in the loop, is now affected by the reversal in polarity and will operate. Relay 55, in operating, opens the operating path of relay 39, above described, in connection with its operation due to the slow release of relay 56. Relay 39, however, will still remain locked up to ground 34. Relay 55 closes through its contacts the ground 34 to the winding of relay 49 which operates.

It may here be explained that upon operating, relay 49 prepares a ground circuit through its outer right hand armature contacts to the winding of relay 23 to prevent relay 23 releasing later when relay 38 operates and opens its contacts 37. Relay 49 also prepares a locking path for itself through the normal left hand contacts of relay 48 and inner right hand alternate contacts of relay 38, (relay 48 being operated through the outer left hand operated contacts of relay 39 when relay 39 operated). Relay 49 in operating now opens the operating path of relay 48 by pulling up its inner right hand armature and closes a path to the winding of relay 38 which operates in the following circuit: battery, winding and outer right hand normal contacts of relay 38, inner left hand operated contacts of relay 39, middle right hand operated contacts of relay 49, alternate contacts of relay 55 to ground at 34 through the usual path. Relay 38 will immediately lock up to ground 34 through its outer alternate right hand contacts.

The operation of relay 38 closes ground at its inner right hand alternate contacts through the operated contacts of relays 48 and 49 to a point 63, between relays 54 and 55. This condition exists as long as relay 48 remains operated, after its operating path is opened by relay 49, relay 48 being slow to release. The function of this ground in shunting down relay 258 in the tie line on the front cord will be herein-after shown.

Now will be described the circuit condition in the tie line with the front cord in the tie line jack, i. e. the tie line forwarding the call on a through tie line connection, the in-

coming call having been answered with the rear cord as just described. As hereinbefore observed, when the front cord is in an associated tie line jack, relays 235, 245, 223, 220, 258 and 242 are operated. When the rear cord is in another tie line jack, relay 103 in the cord circuit is operated in the circuit from the current source at 257 in the tie line associated with the front cord, 10 through the cord and the dry bridge of relays 54 and 55 in that tie line circuit (i. e. on the rear cord), as hereinbefore explained. Relay 103 in operating closes the circuit in the cord, to relay 115 which operates from 15 battery 104 to ground at the jack through the alternate contacts of relay 103. The operation of relay 115, changes the comparatively low resistance bridge in the cord circuit comprising winding 111 of coil 107, to a much 20 higher resistance bridge now including windings 111 and 161 in series. This bridging circuit, in the cord alone, includes the tip conductor, contacts 110 of key 109, windings 111 and 161 of coil 107, alternate left 25 hand contacts of relay 115, contacts 116 of key 109, to ring of the line. This bridge in the cord, it may be observed, bridges the circuit heretofore described that extends from the battery associated with coil source 30 257 in the line on the front cord, through the cord, and relays 54 and 55, etc. in the tie line on the rear cord, back to ground 234. As a result, relays 242 and 258 in the tie line on the front cord are, held by the dry 35 bridge consisting of relays 54 and 55 in the tie line on rear cord, in multiple with the dry bridge in the cord circuit comprising windings 111 and 161; and also by retardation coil 162 in the attendant's "talk and dial front" circuit, which is also bridged across the line due to the actuation of key 164 and the consequent operation of relays 163 and 114 as follows: Upon the necessary operation of talk and dial front key 164 (in order 40 to ascertain what disposition is to be made of the call going through) relay 163 will close a circuit from battery and winding thereof, normal contacts of monitoring key 165, lower operated contacts of key 164, 45 lower normal contacts of relay 166 to ground at armature of relay 167. Relay 114 will thereupon operate through upper operated contacts of relay 163, upper contacts of of key 164 to ground at inner armature of relay 167. The operation of relay 114 closes ground to relay 166, which causes the energization of the secondary winding of relay 163. As a result, retardation coil 162 is bridged across the cord, the obvious 50 paths including normal contacts of relay 168 and the outer alternate contacts of relay 163.

To proceed with the through tie line circuit operation, when relay 55 in the tie line circuit on the rear cord operated (on reverse

battery), and caused the operation of relays 49 and 38,—ground was connected to the rear tie line circuit as above related, to a point 63 between relays 54 and 55. The relay 258 in the tie line on the front cord will 55 then release, due to the arrangement of the high resistance bridges and primarily the shunting of the current through it (which comes from source 257) below its releasing value. Relay 242, however, is not so affected and remains operated on this current. Relay 258 releases slowly and closes ground through the operated contacts of relay 242. Relay 242 then locks up as follows: Battery, 60 secondary winding and inner contacts of relay 242, normal armature contacts of restored relay 258 to ground 234. Relay 258 by restoring also and principally serves to connect ground to relay 211 after it short circuits the primary winding of relay 242 in 65 an obvious circuit. Incidentally, it may be noted that relay 242 remains operated on its short circuited primary long enough for the contact on relay 258 to close the circuit to its secondary as above described. Relay 211 70 75 operates slowly in a circuit through the inner operated contacts of relay 242 and normal contacts of relay 258 to ground 234. Upon its energization, it obviously opens the repeating coil 213 from the tip and ring of the line. In consequence, the dry bridge of the cord circuit is disconnected from the winding of relay 258. This operation consisting of the release of relay 258 and the operation of relay 211 occurs before slow to 80 release relay 48 in the tie line on the rear cord releases.

When the battery associated with coil 257 is removed by the operation of relay 211 on the front cord, relay 55 in the tie line on the rear cord releases and thus opens the operating circuit of relay 49. Inasmuch as relay 48 has not yet released up to this time, relay 49 fails to find a holding ground through the normal contacts of relay 48, and will therefore release. Relay 49 by opening its outer right hand contacts opens the ground to the winding of relay 23. Relay 23, however, will still find a holding ground at 34 as long as relay 62 remains normal, through the inner left hand alternate contacts of relay 38, normal contacts of relay 62, inner right hand alternate contacts of relay 37, to ground 34 through the usual path. However, as soon as relay 49 completely releases, relay 62 operates through its outer left hand restored contacts and the inner right hand alternate contact of relay 38 to ground 34. Upon the operation of relay 62, it opens the ground connected to the sleeve of the tie line circuit and to relay 38. Relay 38 as a result loses its holding ground and releases, thereupon obviously causing relay 20 to release also. Relay 23, in releasing and opening its outer left hand operated contacts opens the 85 90 95 100 105 110 115 120 125 130

ground to relay 39 which releases. When slowly releasing relay 48 finally releases, it opens the ground connected to the line (i. e. from point 63 at relay 55 through operated contacts of relays 48, 49 and 38 as heretofore explained) and consequently causes its connection (i. e. from ground 34) through the inner right hand alternate contacts of relay 38, normal outer right hand contacts of relay 48, inner right hand normal contacts of relay 49, to winding of relay 11, which operates and obviously disconnects the repeating coil 13 and associated equipment from the tie line on the rear cord.

15 Thus, with the operation of relays 11 and 211 in the tie lines on the rear and front cords respectively, the repeating coils are cut out and the tie lines are connected directly through the local cord. It may be noted that it was by the mere insertion of the front plug in the tie line jack, that this condition was brought about due to the reception, recognition, and proper execution in the tie line on the front cord of the particular affecting operating condition of the tie line on the rear cord.

With the through tie line condition brought about, a description will now be given relative to flashing of the supervisory lamp in the cord circuit while this through connection is being set up. When the front cord is inserted in a second tie line jack, after the rear cord has been inserted in a tie line jack, the supervisory relay 103 in the cord circuit is operated. As a result, supervisory lamp 101 is kept extinguished. However, when the relay 105 in the cord circuit operates in series with starting relay 235 in the sleeve of the tie line on the front cord as heretofore described in detail, and as a result of said operation battery 104 and ground at the right hand armature of relay 105 are reversed from the cord circuit, relay 103 releases and causes supervisory lamp 101 to light.

Soon after, as was observed, relay 220 in the tie line on the front cord operates, and connects the reverse battery 257 to the cord circuit. This operates relay 103 again, and thus extinguishes lamp 101. Then, when the ground is connected by relay 38 to the ring of the tie line on the rear cord, relay 103 is shunted down momentarily due to a reversal of current flow through it caused by the shunting of the ground from the front cord, by the rear cord tie line. This sudden lapse prior to its operation on reverse battery, is sufficient to momentarily light the supervisory lamp. However, as soon as relay 103 operates on the reverse current it extinguishes the lamp again. From a practical standpoint this flash may not be noticed. There is another flash due to battery 257 being removed by relay 211 in the front cord. This allows relay 103 to release be-

fore the sleeve ground serving lamp 101 is removed by the operation of relay 62 in the rear cord tie line. When however, this ground is taken off the sleeve, lamp 101 is extinguished and remains so until either distant interconnected exchange re-rings, as will now be explained.

Clearly, on an outgoing ring on through tie line connections, the ringing current is applied directly to the line by means of the usual ringing key bridged thereacross in the cord. No relays, therefore function under this condition. However, on re-rings from either distant tie line on through tie-line connections, after relays 11 and 211 have operated in the respective tie lines and the ground is removed from the sleeve of the rear cord by the operation of relay 62, non-locking supervision is given to the cord circuit as follows: relay 64 is bridged across the tip and ring of the rear tie line through the inner middle left hand contacts of relay 38 which is connected directly through to the tie line on the front cord. Relay 64 will operate on a ring from either tie line and will, by pulling up its armature, restore relay 62, which in turn connects ground from 34 to the sleeve of the rear cord through the operated inner right hand contacts of relay 38, restored contacts of relay 62, inner left hand alternate contacts of relay 38, through normal right hand contacts of relay 35 to the sleeve of the rear cord. As a result, rear supervisory lamp 101 will find a ground and remain lighted as long as relay 64 is operated, thus signaling the attendant.

In considering the use of this tie line with reverse battery central office trunks, it may be noted that as a general rule in manual and full mechanical power driven machine switching systems, negative battery is supplied over the ring of the line and ground, i. e. positive battery is connected to the tip, whereas in the usual step-by-step machine switching system, negative battery is connected to the tip, and ground is connected to the ring of the line. As has been noted, the tie line circuit arrangement herein described is designed to operate equally well with battery fed in either direction. Considering the forwarding of a call from a tie line to a reverse battery central office trunk, it should be noted that when the rear cord is in the tie line jack, relay 54 (using Fig. 3 for illustration purposes) is operated on the battery 104 from the cord circuit, in turn holding relays 41 and 56 operated. Relays 35, 45 and 39 operate and release, and relays 23 and 20 operate and lock up, all as heretofore particularized. Relay 54 is, as also explained, held up due to the rear cord being in the jack. Now, when the front cord is inserted in a central office jack, as for example, 301 of Fig. 1^a which illustrates a central office trunk, Y, terminating in the

private branch exchange and adapted to be connected to an associated central office, for example X; relay 105 in the cord operates in series with relay 302 in the central office 5 trunk, which closes and supplies battery to the sleeve of the trunk jack. The circuit path is: battery and winding of relay 302, sleeve of the jack (into which the front plug of the cord circuit is inserted to close the 10 local contact) through the winding of relay 105 to ground. Relay 105 thereupon energizes and removes battery 104 and ground at its inner right hand armature from the 15 cord, thus allowing relay 54 in rear tie line to release.

At this time or immediately after, relay 302 by operating obviously connects battery on the tip and ground on the ring of the cord circuit from the central office. This 20 reversal of battery and ground causes the polarized relay 54 to release, if it is still operated, and in turn causes relay 55 which functions on current of opposite polarity to operate. The turnover is so rapid that relay 25 54 in releasing closes the circuit to relay 39 (as has heretofore been described) only momentarily, and therefore relay 39 does not have time to operate and lock up before relay 55 in operating, opens (as has been 30 shown heretofore) the operating circuit for relay 39. This is effected purposely in order to prevent relay 39 and thence relay 38 from operating and thus to keep relay 11 from functioning to cut out the repeating coil. 35 By this device, relay 11 remains normal.

To proceed, relay 55 closes the circuit to relay 49 which operates through the alternate contact of relay 55 to ground 34 but inasmuch as relay 39 has not operated, relay 40 49 does not perform any function at this time. The bridge in the tie line, consisting of relays 54 and 55 holds supervisory relay 103 in the cord circuit operated, thus keeping lamp 101 extinguished, and causing relay 115 to operate. As has been fully explained, the operation of relay 115 changes 45 the bridge in the cord circuit from one of low resistance including only resistance 111, to one of very high resistance including 111 and 161 of coil 107. Because of this, as has been analogously shown heretofore, the bridges in the cord circuit and tie line hold the central office connection operated.

Supposing that a distant private branch 55 exchange connected as just described to a central office, wished to re-ring the attendant at the local P. B. X. (as for example Boston in Fig. 2^a desiring to re-ring New Haven when connected therethrough to central office 60 V) the following operation could take place:—The distant operator, on a recall or disconnect re-ring, when the rear cord is in the tie line jack and the front cord in the central office jack, would actuate the usual

ringing key, whereupon relay 10 operates 65 and connects ground from lead B to a point 65 between resistance 66 and relay 20. This, in effect causes relay 20 to restore inasmuch as it is now short circuited, by the battery 70 51 proceeding directly to ground at lead B of Fig. 1^b, the normal arrangement, (instead of through the winding of relay 20 etc. to ground 34, as hereinbefore shown). The release of relay 20 opens the dry bridge 75 consisting of relays 54 and 55, from across the cord circuit (thus opening the loop from the control office battery) in turn causing relay 103 to release. This closes the circuit for supervisory lamp 101, which consequently remains lighted as long as the ring is coming in from the distant exchange. The relays 54 and 55 in releasing perform no useful function. At the end of the ring, relay 10 releases, thereby removing the short circuit 80 from battery 51 and allowing relay 20 again to operate and restore the circuit to its condition prior to the re-ring.

The condition and operation of the tie line on an outgoing call thereto from a reverse battery central office, will in turn, now be 90 described. Upon the flash from the central office, the front cord is connected to the central office trunk, as that shown in Fig. 2^a. The connection of the call to a tie line is then effected by inserting the rear cord in 95 the tie line jack, for illustration, that of Fig. 3. After the front cord is connected to said central office trunk, which feeds reverse battery to the cord circuit, relays 35, 39, 45, 23 and 20 operate consecutively as 100 heretofore described in that part of the description dealing with the answering of incoming calls with the rear cord. As shown, relays 35 and 45 release, relay 23 locks up and holds relay 20 operated, and relay 39 105 locks up under the control of relays 41 and 42.

Due to the reverse battery on the tip and ring of the rear cord from the central office trunk, polarized relay 55 will now operate 110 (instead of relay 54), and in turn operate relay 49 to ground 34 as heretofore shown. Relay 39, in locking up, closes the circuit to relay 48 which operates through left hand inner normal contacts of relay 49, the outer 115 left hand alternate contacts of relay 39 to ground 34 through contacts 37 of relay 38. Relay 48, however, performs no useful function by its operation at this time. Relay 49, in operating obviously opens the circuit 120 to relay 48 which begins to release slowly. Relay 39, being locked up, completes through its inner alternate contacts the path from battery and the winding of relay 38 to the middle right hand alternate contacts of 125 relay 49, through alternate contacts of relay 55 to ground 34, as heretofore described. Relay 38, therefore operates and connects

ground to the line through the operated contacts of relays 48 and 49 as long as relay 48 remains operated after relay 49 opens its energizing circuit, as heretofore explained. 5 This ground is connected from 34 through the inner right hand alternate contact of relay 38, outer left hand alternate contact of relay 49 and left hand alternate contact of relay 48 to the line through relays 55 10 and 54 etc. When slow to release relay 48 finally releases, it removes the ground from the line and closes a locking path through its left hand contacts for relay 49 to ground through the inner right hand operated contacts of relay 38, thus removing relay 49 15 from the control of relay 55.

With the circuit condition as above described (that is, with the rear cord in the tie line jack and the front cord in a reversed central office trunk), an outgoing ring 20 on the tie line is effected as follows: The operation of the ringing key in the cord circuit, after relay 48 has released, causes ringing relay 53 to operate in an obvious path, 25 which in turn causes relay 12 to operate in a circuit from battery and winding of relay 12, inner alternate contacts of relay 53, inner operated contacts of relay 23, outer operated contacts of relay 23, outer right hand 30 alternate contacts of relay 49 to ground at 34. The operation of relay 12 thus connects ringing current to the line circuit to ring the distant exchange. It may be observed 35 that the ringing current causes relay 64 to function but no useful result is performed as the circuit to relay 62 is open at the outer alternate contacts of relay 49. When the ringing key is restored in the cord, relay 53 restores, allowing relay 12 to release, and 40 the ringing of the distant exchange to cease.

If, however, the ringing key is operated before the relay 48 has completely restored, relay 55 releases, in turn releasing relay 49, inasmuch as the locking circuit for relay 45 49 is open at relay 48 (at its left hand operated contacts). Hence, if relay 49 releases before slow to release relay 48 closes its back contact, the circuit to relay 11 heretofore traced through the inner right hand 50 normal contacts of relay 49 etc. is open at the contact of relay 48. Again, when relay 49 releases it closes an operating path for relay 48 from an operated contact of relay 39. This circuit path runs from battery 55 and winding of relay 48, inner right hand normal contacts of relay 49, outer left hand alternate contacts of relay 39, inner right hand alternate contacts and armature of relay 23, inner left hand alternate contacts 60 of relay 38, normal contacts of relay 62 and inner right hand alternate contacts of relay 38 to ground 34.

In case, however, slow to release relay 48 65 perchance releases before relay 49 releases, it closes the locking circuit of relay 49, herein-

before explained, and thus prevents relay 11 from operating on the opening of the central office battery by the ringing key.

It may be explained that it is the purpose here to prevent relay 11 from operating, and thus to prevent the cutting out of the associated repeating coil. This is accomplished by keeping either of relays 48 or 49 operated. The repeating coil is inserted in the tie line circuit in terminating connections with central offices, to prevent the central office from reaching the toll line, and from interfering with toll line apparatus. The releasing coil in association with its auxiliary apparatus (i. e. relays 54, 55, etc.) also provides a holding bridge for the supervisory signal in the cord circuit; and, in addition serves to hold the line central office equipment, in its operated position until the connection is taken down.

To proceed when ringing current is applied by the ringing key in the cord, relay 53 operates and closes the circuit to relay 12 which operates and obviously connects ringing current to the line. Relay 53 also closes a circuit to the back contacts of relay 39 to hold relay 48 operated when relay 39 releases later. Upon the connection of the ringing current to the line, polarized relay 54 will follow the ringing current, and will operate on each half cycle of the ringing current. (Polarized relay 55 will also operate but performs no useful function as its back contact is closed when the contact of relay 54 is operated.) The operation of relay 54, as just described caused relay 41, under its control, to operate as long as the ringing continues. Relay 41 thereupon opens the locking circuit of relay 39 which as shown was held up by ground 34, thus causing relay 39 to release. This transfers the operating circuit of relay 48 from under control of relay 62 to the control of relay 53. In detail, the circuit for relay 48 formerly extended from battery and winding of relay 48, left hand normal contacts of relay 49, outer left hand alternate contact of relay 39, inner right hand operated contacts of relay 23, inner left hand operated contacts of relay 38, normal contacts of relay 62, inner right hand alternate contacts of relay 38 to ground at 34. Relay 48, will now, upon the operation of relay 39, be under the control of relay 53 in a circuit as follows: battery and winding of relay 48, inner left hand normal contact of relay 49, outer left hand restored contacts of relay 39, outer left hand operated contacts of relay 53, inner operated contacts of relay 53, inner left hand operated contacts of relay 38, normal contacts of relay 62, to ground 34 through inner right hand contacts of relay 38. Relay 48 thus stays operated until relay 49 again operates. It may be observed that relay 41, in addition to effecting the release of relay 130

- 39, closes the circuit at its inner contact from ground through the make contacts of relays 48 and 38 to the winding of relay 49 which operates. Relay 49 on operating obviously opens the circuit to relay 48; and if relay 48 releases during the ringing period, relay 49, as heretofore explained, locks up through the contacts of relay 48. It is therefore manifest that by keeping either of relays 49 or 48 operated during this condition of the line, the desired result, that is, of keeping the relay 11 from operating and cutting out the associated repeating coil and loop, is accomplished.
15. Further, in case the ringing key is restored before slow to release relay 48 releases, relay 55 operates on the central office battery and closes the operating path, as described, for relay 49. When relay 48 finally releases, relay 49 locks up directly to the jack ground through contacts of relay 48 and 38 and will not release on further operations of the ringing key.
- The circuit arrangement herein outlined 25. may be used with railway message telephone lines equipped with selector apparatus. If then, for example, a train dispatcher at station *h*, Washington, Fig. 2^a, desires to make connection with another station anywhere 30. in the system, he will accordingly transmit by means of an impulse sending key (not shown) a code which would actuate the selector 68 (Fig. 3^c) at the inward end of the line at the Washington private branch exchange. It will be assumed that selector 68 moves its arm 69, under control of the transmitted impulse code, into engagement with terminal 70 thereby connecting ground to the right-hand winding of relay 67 and 35. causing its operation. Relay 67 in operating connects ringing current to the winding of relay 10, and ground to the armatures thereof. Upon the operation of relay 10, the circuit is closed to relay 17, as previously 40. described to light the line lamp and set the busy signal, etc. The call is then answered and forwarded as previously described in detail in that part of the foregoing description dealing with the answering 45. of incoming calls.
- In accordance with the monitoring feature of this invention, when monitoring key 165 is operated, the circuit to relay 167 is obviously closed. Relay 167 thereupon operates and opens the ground on lead 169. This is done for the purpose of releasing relay 114. (of this or other strapped cords) which may be operated if the attendant has failed to release all the talking keys, as 164. 55. Relay 167, by pulling up its outer armatures, obviously disconnects the telephone receiver from induction coil 170 and connects it across the low impedance winding 172 of the monitoring transformer 171. Relay 167
- also connects ground to relay 168 at its inner left hand armature.
- Relay 168 operates and connects ground at its middle left armature to cause the operation of relay 163. The operation of relay 168 however, opens its inner and outer normal contacts to prevent the connection of the induction coil 170 of the operator's telephone set to the talking conductors of the cord and by closing its contacts 174 and 175 connects the three serially connected high impedance 70. windings 176, 177 and 178 of transformer 171 thereto, instead. The operator's receiver 173 is thereby connected, through the monitoring transformer 171, to the talking conductors of the cord, without the incident 80. transmission loss which takes place when the operator listens in with the regular talking and listening circuit which includes the relatively low impedance induction coil 170.
- It will be noted that the operation of relay 85. 167 removes ground from conductor 169 as hereinbefore mentioned thereby preventing the operation of relay 163 of another cord, when the corresponding talking key is operated, thus in turn preventing the connection 90. of this cord to the cord on which the monitoring key is operated through the operator's telephone set circuit.
- On receipt of the disconnect signal as described, the connection is taken down in the 95. usual manner, and the circuit restores to normal.
- What is claimed is:
1. In a telephone system, a plurality of private branch exchanges, tie lines extending therebetween, repeating coils normally included in each tie line at each exchange, a link circuit at one of said exchanges for interconnecting two of said lines, and means included in said two lines 100. responsive to their interconnection for excluding said repeating coils from the connected ends of said two lines.
  2. In a telephone system, a plurality of private branch exchanges, tie lines extending therebetween, repeating coils normally included in each tie line at each exchange, a link circuit at one of said exchanges for interconnecting two of said lines, and means 110. included in said lines responsive to the interconnection of said two lines by said link circuit for excluding said repeating coils from the connected ends thereof, and for substituting therefor a relatively low impedance path.
  3. In a telephone exchange system including a plurality of private branch exchanges, tie lines extending therebetween and terminating thereat, subscribers' and central office lines also terminating at certain of said exchanges, cord circuits at said certain exchanges for interconnecting certain of said lines and said tie lines, repeating coils nor-

5 mally included in each end of each of
10 said tie lines, means also included in
15 each of said tie lines responsive to the in-
terconnection of two such lines by one of
20 said cord circuits for excluding said repeat-
ing coils from the interconnected ends of
25 said lines, and other means also included in
30 said tie lines and cooperating with said cord
35 circuit, responsive to a connection between
40 one of said tie lines and a subscriber's line
45 for supplying talking battery through said
50 tie line to the connected subscriber's line
55 when a particular end of the connecting
60 cord circuit is associated with the tie line
65 and for excluding said battery when the
70 other end of said cord is associated with said
75 tie line.

4. In a telephone exchange system includ-
20 ing a plurality of private branch exchanges,
25 tie lines extending therebetween and ter-
minating thereat, subscribers' and central
30 office lines also terminating at certain of
35 said exchanges, cord circuits at said certain
40 exchanges for connecting certain of said
45 lines with said tie lines, and means included
50 in one of said tie lines responsive to its con-
55 nection with one of said subscribers' lines
60 for supplying talking battery through said
65 tie line to the connected subscriber's line
70 when a particular end of said cord is con-
75 nected with said tie line.

5. A telephone system comprising a plu-
30 rality of private branch exchanges, inter-
35 exchange tie lines therebetween, and ter-
minating thereat subscribers' and central
40 office lines also terminating at said ex-
45 changes, cord circuits at said exchanges
50 for interconnecting said various lines,
55 said tie lines being arranged to include
60 a repeating coil in the talking path on a
65 tie line to subscriber's line or tie line to cen-
70 tral office line connection via one of said
75 cord circuits and means individual to each
80 tie line responsive to the connection of one
85 tie line to another tie line for providing a
90 through talking path from said one tie line
95 to said other tie line exclusive of said re-
peating coils.

6. In a telephone system, a private branch
50 exchange, a plurality of tie lines terminat-
55 ing thereat, subscribers' lines and cen-
60 tral office trunks also terminating there-
65 at, a cord circuit thereat adapted to in-
70 terconnect two of said tie lines and for
75 connecting one of said tie lines with one of
80 said subscribers' lines or with one of said
85 central office trunks, and for connecting one
90 of said subscribers' lines with one of said
95 central office trunks or with another sub-
100 scriber's line, repeating coils associated with
105 each of said tie lines at said exchange and
110 included therein on connections between
115 said tie lines and said subscribers' lines or
120 central office trunks, and means included in
125 each of said tie lines responsive to the inter-

connection of two of said tie lines for estab-
130 lishing a through low impedance talking
135 path from one tie line to the other to the
140 exclusion of said repeating coils.

7. An intercommunication system includ-
145 ing a plurality of private branch exchanges
150 interconnected by tie lines, cord circuits at
155 each of said private branch exchanges for
160 interconnecting the lines connected thereto
165 and those outgoing therefrom, means actu-
170 ated upon the connection of one end of
175 one of said cords with one of said tie lines,
180 whereby upon the connection of the other
185 end of said cord with another of said tie
190 lines, the repeating equipment in both said
195 tie lines is cut out, and the tie lines con-
200 nected directly through the cord.

8. An intercommunication system includ-
205 ing a plurality of private branch exchanges,
210 tie lines for interconnecting said exchanges,
215 cord circuits at each said exchange, repeat-
220 ing equipment included only in said tie lines
225 and means whereby upon the interconnec-
230 tion of two said tie lines by one of said
235 cord circuits, said repeating equipment in
240 each of said interconnected tie lines is ex-
245 cluded from the connection due to mutual
250 recognition in each said tie line of the de-
255 sired operating condition.

9. An intercommunication system includ-
260 ing a plurality of private branch exchanges,
265 tie lines for interconnecting said exchanges,
270 cord circuits at each said exchange for ex-
275 tendsing said tie lines to associated sub-
280 scribers' lines, to central office lines and to
285 other tie lines, repeating equipment in said
290 tie lines, and means actuated only upon the
295 connection of one tie line by one of said
300 cords to another tie line, for removing the
305 repeating equipment in both said intercon-
310 nected tie lines.

10. A telephone line, a cord circuit in-
315 cluding a supervisory signal therefor, a re-
320 peating coil normally included in said line,
325 polarized relays adapted to be bridged across
330 said line, and means actuated upon the con-
335 nection of said line and cord circuit for
340 bridging said relays across said line to con-
345 trol said signal.

11. A telephone system including a pri-
350 vate branch exchange, tie lines terminat-
355 ing thereat, a repeating coil individual to each
360 of said tie lines, a cord circuit for intercon-
365 necting said tie lines, means responsive to
370 the connection of one end of said cord cir-
375 cuit with one of said tie lines for connecting
380 a dry bridge including a winding of the
385 repeating coil individual to said line there-
390 across, and other means responsive to the
395 connection of the other end of said cord cir-
400 cuit with another of said tie lines for
405 excluding said bridge of said first tie line.

12. In a telephone system, in combination,
410 a telephone line, a cord circuit, repeating
415 equipment normally included in said line,

1. Polarized relays adapted to be connected in bridge of said repeating equipment, a current source associated with said cord circuit, means responsive to the connection of said cord circuit with said tie line for operating one of said polarized relays from said current source, two other relays connected in parallel and controlled by said one polarized relay, and another relay controlled by 10 one of said relays in parallel. 13. In a telephone system a tie line, a cord circuit for connecting therewith, a relay in said tie line, a resistance in association with said relay, a relay in said cord circuit, and 15 means actuated upon the connection of a particular end of said cord circuit with said tie line for causing the shunting of the said relay in said tie line by said resistance and the operation of said relay in the cord circuit. 14. In a telephone system, a tie line, a cord circuit adapted to be connected thereto, a current source in said cord circuit normally connected thereto, a current source in 25 said tie line, a repeating coil in said tie line, a plurality of polarized relays in bridge of said tie line, and means controlled upon the connection of a particular end of said cord circuit to said tie line for causing the disconnection of said current source in the cord circuit therefrom, and means for causing the disconnection of said bridged polarized relays from said tie line and the connection of said current source in said tie line to said 35 repeating coil. 15. In a private branch exchange telephone system, an exchange, a tie line and a subscriber's line terminating thereat, a cord circuit thereof, said cord circuit being adapted to connect said lines, switching means in said cord circuit, a dry bridge adapted to be connected across said cord circuit by said switching means, a battery source normally connected to said 40 cord circuit by said switching means, a battery source associated with said tie line, repeating equipment in said tie line, and other means in cooperation with said switching means in the cord responsive to the interconnection of said lines for disconnecting said current source in the cord circuit, for connecting said dry bridge across said cord, and for connecting said repeating equipment to the current source associated with 45 said tie line. 16. In a telephone system, a tie line, a cord circuit, a relay in said tie line operated in response to the connection of said cord to said tie line, said relay controlling a supervisory bridge across said tie line, supervisory signals associated with both ends of said cord circuit, means responsive to a ringing incoming over said tie line for releasing said operated relay to cause the opening of said supervisory bridge to effect a 50 change in the condition of one of said supervisory signals. 17. In a telephone system, a cord circuit, a tie line, a pair of polarized relays in said tie line, means for causing the operation of one of said relays upon the connections of said tie line to one of the ends of said cord circuit, a second tie line, and means actuated upon the connection of said second tie line to the other end of said cord circuit to cause 55 the release of said operated polarized relay and the operation of the other of said polarized relays. 18. A telephone system including a private branch exchange, trunk lines terminating thereat, subscribers' lines and central office lines terminating thereat, a cord circuit thereat for interconnecting said trunk lines and for connecting one of said trunk lines with one of said subscribers' or central office lines, battery sources respectively associated with said cord circuit, said trunk lines, and said central office lines, and means included in each of said trunk lines for discriminating between said respective battery sources, 60 responsive to the interconnection of one of said trunk lines with another of any of said lines. 19. In a telephone system, a cord circuit, a first telephone line, a second telephone line, circuit controlling means in said first telephone line, repeating equipment normally included in said second telephone line, a relay in said second telephone line controlling the connection of said repeating equipment 65 therewith, and means responsive to the connection of said lines by said cord circuits and controlled by said circuit controlling means in said first telephone line for causing the operation of said relay in the second telephone line to cause the disconnection therefrom of said repeating equipment. 20. In a telephone system a first telephone line, a second telephone line, a repeating coil normally included in each of said telephone lines, a source of current associated with each of said lines, a cord circuit adapted to interconnect said lines, a circuit including two polarized relays connected in opposite 70 direction therein associated with each of said lines, means responsive to the connection of said cord circuit with said first line for connecting across said first line said circuit associated therewith including said polarized relays, a source of current associated with said cord circuit adapted to operate one only of said polarized relays upon their connection across said first line, means associated with said second line responsive to the connection of the other end of said cord circuit therewith for causing said cord battery to be disconnected and said operated polarized relay in said first line to be released, means associated with said second line responsive to its said connection with said cord for 75 80 85 90 95 100 105 110 115 120 125 130

causing the said source associated therewith to be bridged thereacross to cause the operation of the other of said two polarized relays in the first line, a relay in said second line, 5 means controlled by the operation of said other polarized relay in said first line for actuating another relay in said first line to shunt said relay in the second line, means including another relay in said second line 10 operated upon the shunting of said first relay in said second line for causing the disconnection of the said repeating coil from said second line and the disconnection of the said source therein from said line, means re- 15 sponsive to the exclusion of said repeating coil from said second line for causing the release of said other of said two polarized relays in said first line, and means actuated thereupon for causing the disconnection of 20 the other of said repeating coils from said first line.

21. In a telephone system, two telephone lines, a cord circuit adapted to interconnect said lines, repeating equipment normally 25 connected in and adapted to be disconnected from said tie lines, means in one of said lines for disconnecting the repeating equipment therefrom in response to the interconnection of said second line, means in the 30 other of said telephone lines for disconnecting the repeating equipment from said telephone line, said means being actuated upon the exclusion of the repeating equipment from the first of said tie lines.

35 22. In a telephone system, a cord circuit, a tie line adapted to be connected to one end thereof, a central office line adapted to be connected to the other end, a pair of polarized relays in said tie line, a current source 40 associated with said cord circuit, a current source of polarity opposite thereto associated with said central office line, means actuated upon the connection of said cord circuit and tie line for causing the operation 45 of one of said polarized relays from the current source in said cord circuit, and means actuated by the connection of the other end of said cord circuit with said central office line for causing the release of said operated 50 polarized relay, and the operation of the other of said polarized relays.

55 23. In a telephone system, a cord circuit, a tie line adapted to be connected to one end thereof, a central office line adapted to be connected to the other end, a first relay in said tie line, two polarized relays associated with said tie line, one of said polarizing relays controlling the operation of said first relay, means responsive to the connection 60 of one end of said cord to said tie line for connecting said polarized relays in series across said tie line and for operating one of said polarized relays, a repeating coil in said tie line normally connected therein and 65 adapted to be disconnected therefrom by

said first relay, means responsive to the connection of the other end of said cord to said central office line for causing the release of said first polarized relay and the operation of the other of said polarized relays, and 70 other means responsive to the operation of said second polarized relay, whereby said first relay is effectively prevented from causing the disconnection of said repeating coil from said tie line. 75

24. In a telephone system a cord circuit, a tie line adapted to be connected to one end thereof, a central office line adapted to be connected to the other end thereof, signaling means in said cord circuit, a dry bridge associated with said tie line, a dry bridge associated with said cord circuit including resistance means adapted to be varied, means for assuring the maintenance of said signaling means in a desired condition, and means responsive to the interconnection of said lines by said cord for changing the resistance in said bridge across the cord to assure the maintenance of the connection of said tie line with said central office line. 80

25. In a telephone system, a tie line, a central office line, a cord circuit for interconnecting said lines, a relay in said tie line responsive to ringing current, a second relay in said tie line, a dry bridge associated with said tie line and connected thereacross responsive to the connection of said cord to said tie line, signaling means in said cord circuit, and means actuated upon the connection of the other end of said cord with said central office line whereby upon the operation of said relay responsive to ringing current said second relay is caused to open said dry bridge to control the operation of said signaling means. 90

26. In a telephone system, a cord circuit, a current source associated therewith, a tie line and a central office line adapted to be interconnected thereby, polarized relays associated with said tie line, means including a current source associated with said central office line connected in a reverse direction to that in the cord circuit for causing the actuation of certain of said polarized relays, a second relay caused to operate by the actuation of said polarized relay, said second relay causing the operation of a third relay to close a locking path for said second relay, upon the release of a fourth relay controlled by said second relay. 100

27. In a telephone system, a tie line, a central office line, a cord circuit adapted to interconnect said lines, means in said tie line including a first relay under the control of a second relay therein, another relay in said tie line responsive to ringing current, repeating equipment in said tie line, means for disassociating said repeating equipment from said tie line, and means responsive to the operating of said ringing relay for as- 110 120 125 130

suring the operation of either of said first and second relays to maintain the connection of said repeating equipment to said tie line.

- 5 28. In a telephone system, a private branch exchange, interexchange tie lines and a railway message line terminating thereat, a line signal for said railway line at said exchange, a cord circuit thereat adapted 10 to interconnect said railway line and one of said tie lines, repeating coils normally included in and individual to each of said lines at said exchange, means including a selector in said railway line, responsive to selective 15 impulses transmitted thereover to cause the operation of said line signal, and means responsive to the interconnection of said railway line and one of said tie lines by means of said cord circuit for excluding said repeating coils from said interconnected lines.

- 20 29. In a telephone system a first tie line, a second tie line, a cord circuit for interconnecting said tie lines, a signal in said cord circuit, and means in said first tie line 25 operative responsive to the application of ringing current in said second tie line for causing the actuation of said signal.

- 30 30. In a telephone system a tie line connecting a first and a second P. B. X., another tie line connecting said first and a third P. B. X., a cord circuit for interconnecting the ends of said tie lines terminating at said first P. B. X., a signal in said cord circuit, and means in the end of one 35 of said tie lines associated with said cord circuit operative responsive to the application of ringing current at the ends of the tie

lines terminating in said second or third P. B. X.'s for causing the actuation of said signal in the cord.

31. A P. B. X. telephone system comprising a plurality of tie lines interconnecting a first P. B. X. with other P. B. X.'s, equipment in said tie lines at each of the terminating ends thereof including repeating coils, a cord circuit and means responsive to the interconnection of two of said tie lines by said cord circuit for excluding the repeating coils from the interconnected ends of said tie lines and preparing other means in the connected end of one of said interconnected tie lines operative thereafter responsive to the application of ringing current in the distant end of either of the interconnected tie lines for causing the actuation of a signal in said cord circuit.

32. In a telephone system, a first trunk circuit terminating at exchanges A and X, a second trunk circuit terminating at exchanges A and Y, a cord circuit for interconnecting the ends of said circuits terminating at exchange A, and means responsive to the interconnection of said trunks by said cord and the application of ringing current to said trunks at exchanges X or Y for causing the actuation of means in the connected end of a certain one of said trunks to cause the operation of a signal in said cord.

In witness whereof, we hereunto subscribe our names this 31st day of December A. D., 70 1924.

LANGFORD J. BOWNE.
HORACE W. ULRICH.
